No. 739,592.

PATENTED SEPT. 22, 1903.

J. E. ELMENDORF.
WINDOW SCREEN.
APPLICATION FILED APR. 27, 1903.

NO MODEL.

UNITED STATES PATENT OFFICE.

JOHN EMERICK ELMENDORF, OF NEW YORK, N. Y.

WINDOW-SCREEN.

SPECIFICATION forming part of Letters Patent No. 739,592, dated September 22, 1903.

Application filed April 27, 1903. Serial No. 154,447. (No model.)

To all whom it may concern:

Be it known that I, JOHN EMERICK ELMENDORF, of the city, county, and State of New York, have invented certain new and useful 5 Improvements in Window-Screens, of which the following is a full, clear, and exact description.

My invention relates to improvements in window-screens; and the main object of my 10 invention is to produce a simple form of adjustable screen which will project from the window so as to form a screened recess. This, it will be seen, enables a person to thrust his 15 head from the window and look through the screen up and down the street, which cannot be done with an ordinary flat window-screen. Furthermore, by projecting the screen as 20 herein described, the air-currents are caught and deflected into the building through the window-opening, a better ventilation is therefore afforded, and the receptacle formed by the projecting screen serves to receive articles which it may be desired to keep cool or which 25 may be placed therein to air—as, for instance, bedclothing.

Other objects of my invention are to construct the screen in a simple and substantial manner and yet in such a way as to make it 30 adjustable to windows of somewhat varying width, to the end that it may easily be placed in position and fitted.

Still other objects are to construct and arrange the several parts so that the screen can 35 be easily and securely fastened in place and so that it will be durable and will generally serve the purposes of a well-ventilating screen.

With these and other objects in view my invention consists of certain features of construction and combinations of parts, which 40 will be hereinafter described and claimed.

Reference is to be had to the accompanying drawings, forming part of this specification, in which similar figures of reference refer to similar parts throughout the several views.

45 Figure 1 is a front elevation of my improved screen as applied to a window. Fig. 2 is a plan view of the same. Fig. 3 is a detail section on the line 3 3 of Fig. 2. Fig. 4 is a broken vertical section showing the arrangement of one of the side posts or rods of the 50 screen. Fig. 5 shows a form of binding strip or clip for attaching the screen-body to one

of the supporting-posts. Fig. 6 is a detail section on the line 6 6 of Fig. 4. Fig. 7 is a broken detail perspective of a form of binding-clip. Fig. 8 is a plan view showing a modified form of the screen, and Fig. 9 is a plan view illustrating still another modification of the screen.

In carrying out my invention the main object is to produce a simple form of projecting screen, and while I shall describe a preferred means of carrying this object into effect, still I do not limit myself to the precise construction which I have shown. The preferred form 60 of screen is triangular in cross-section, as shown by the plan in Fig. 2, and it comprises two side members of the screen, which are secured to the side posts or rods on the window-frame and which are hinged at their 70 meeting points, so that the screen may thus be readily adjusted to fit any usual width of window. To this end the screen is provided with supporting side posts 10, which have near the upper and lower ends shoulders 10^a 75 and which carry the screen proper, 12. The screen-body is connected with the side post by means of suitable strips or clips 11, which are bent so as to fit the posts 10, and the opposite side portions of which are squeezed or 80 clamped to the screen. Hereinafter I shall refer to several means of effecting this fastening. Obviously the side rods or posts 10 may be supported in several ways; but I prefer to use the socket-brackets 13, which are fastened at points adjacent to the top and bottom of the screen to the window-frame 14, the socket-brackets having for this purpose bracket-plates 15, which fit against the sides 85 of the frame 14 or other suitable support. 90

In order that the side post may be held tightly and yet easily pushed to place, the upper and lower sockets 13 are provided with inclined ways 16, (see Fig. 6,) which terminate in seats 16^a, and the posts 10 may be 95 easily pushed through these ways and will then squeeze into their seats 16^a, where they will rest securely. Instead of having both upper and lower sockets provided with the inclined way 16 it may be omitted from one 100 without injuring the effect, and it will be evident, too, that other forms of rod-support can be used without departing from my invention.

The opposite sides of the clips or binding-strips 11 may be fastened in several ways. For instance, one may be provided with a slot 17, the other may have a lug 18 struck up from it, as in Fig. 7, and when the parts are pushed together the lug may be thrust through the slot and clenched. To get a good grip on the screen 12 or the top and bottom screen 12^a, presently referred to, the clip 11 may be corrugated, as at 19 in Fig. 6, or the corrugations may extend longitudinally of the clip, as at 19^a in Fig. 3. These binding-strips are used on the side edges and top and bottom of the screen, as will presently appear.

15 The meeting side portions of the screen are connected at the center by means of strips 20, which have hinge-knuckles 21 formed on them, through which runs an ordinary pintle having nuts 22 at top and bottom. The strips 20 are like the strips 11 in that they are corrugated either at 19 or 19^a, so that they shall have the right grip on the screening. Thus it will be seen that the screen may be bent or pushed in or out in the center, so that the 25 sides may be conveniently fastened without regard to the width of the window. The object of the nuts 22 is to prevent the displacement of the pintle and also to bind in place the rods 24, which extend from the rods 10 to the central pintle at the top and bottom of the screen, the ends of the rods being formed into suitable hooks, as shown in the drawings, (see Figs. 1 and 4,) to extend around the pintle and the rods 10.

30 35 The bottom and top of the screen are substantially alike, being formed of the rods 24, just described, and a rod 23, which extends straight across the window-frame, the ends of the rods 23 engaging the rods 10 near the shoulders 10^a, as shown in Figs. 2 and 4. The socket-brackets 13 should be adjusted in relation to the window-sashes so that the cross-rod 23 shall be flush against the bottom of the upper sash, thus rendering the screen insect-proof. The rods 23 and 24 are provided with suitable binding strips or clips 11, substantially like those already described, except that the clips on the outer edges of the top screen 12^a are squeezed together and 40 formed into hooks 11^a, adapted to engage the clips 11 on the rods 24, as shown clearly in Fig. 3. Thus all the parts of the screen are conveniently and securely fastened together, and they can be easily adjusted. In placing 45 the screen in the window the socket-brackets 13 are first secured at the necessary points, the rods 23 and 24 of the top are placed in engagement with the side rods 10, the upper ends of the latter are inserted in the top 50 brackets 13, the bottoms of the rods 10 are then brought close to the lower brackets 13, and the lower rods 23 and 24 are placed in engagement with the lower ends of the rods 10 when the latter are pushed to their seat, and 55 the whole screen is thus in position for use.

60 It will be seen that a projecting or balcony

screen is thus formed in which any articles can be placed which it is desirous to keep cool and that perfect ventilation is afforded.

I do not limit my invention to the triangular form of screen described, as many modifications may be used. For instance, the screen may be bowed out in the form of a cylinder-section, as in Fig. 8, or it may be carried out as in Fig. 9, where it has a flat outer 75 face and two hinge-pintles instead of one. Likewise other projecting forms may be devised without departing from the principle of the invention.

70 It will be seen that by providing a projecting screen, and especially one with the inclined sides, I am able to divert the air-currents so as to enable them to enter forcibly into a room, and thus thoroughly ventilate and cool the same. I also wish to call attention 85 to the fact that, if desired, the brackets 13 may be placed as far apart as need be—as, for instance, near the top and bottom of the window—and the rods 10 made long enough so that the whole screen may be pushed up or 90 down, so as to cover any part of the window open.

Having thus described my invention, what I claim as new, and desire to secure by Letters Patent, is—

95 1. A window-screen comprising two main body portions hinged at their meeting edges, fastening devices for securing the said body portions to a window-frame, and a suitable top and bottom of screening adapted to be 100 fastened to the window-frame and the body portions and form the top and bottom of the screen, the said top and bottom being at substantially right angles to the plane of the body portion of the screen.

105 2. A window-screen comprising two main body portions having their meeting edges provided with engaging hinge-knuckles, fastening-rods to secure the side edges of the screen-body to a window-frame, suitable sockets to receive the rods, said sockets being adapted for attachment to the window-frame, and top and bottom sections secured to the side rods and adapted to close over the top and bottom respectively of the screen.

110 3. A window-screen, comprising hinged body portions, vertically-arranged side rods secured to the edges of the body portions, sockets adapted to be fastened to a window-frame and to engage the side rods, and top 115 and bottom screen-sections connected to the side rods and adjustably fastened to the hinged portion of the screen.

120 4. A window-screen, comprising two main body portions hinged at their meeting edges, 125 supporting-rods secured to the sides of the screen, sockets adapted to engage the supporting-rods and to be fastened to a window-frame, and top and bottom screen-sections, said sections having at their edges rods which 130 are adapted to engage the side rods of the screen and the hinge-pintle.

5. The combination with a projecting window-screen, of rods secured to the edges thereof and sockets adapted to be fastened to a window-frame, the said sockets having inclined entering ways merging in seats, into which ways, the supporting-rods are pushed to engage the seats.

6. A window-screen comprising two main body portions hinged together at their meeting edges whereby the angle between the body portions can be altered, fastening devices for hinging the body portions to the window-frame, a triangular top portion, and a triangular bottom portion.

15 7. A window-screen comprising vertically-disposed sections hinged to one another, and on the extreme outer edges to the window-

frame, and horizontal top and bottom portions.

8. A window-screen comprising rectangular body portions pivotally arranged in relation to one another whereby the distance between the extremes can be regulated, means for pivotally securing the extreme edges to a window-frame whereby the frame can be fitted to different sizes of windows, a removable top portion, and a removable bottom portion.

In testimony whereof I have signed my name to this specification in the presence of two subscribing witnesses.

JOHN EMERICK ELMENDORF.
